UNITED STATES PATENT OFFICE.

CLARENCE L. GRAVES, OF ELAND, WISCONSIN, ASSIGNOR OF ONE-HALF TO LAVES OLESON, OF ST. PAUL, MINNESOTA.

DESIGN FOR A KITCHEN-TOOL.

59,076.

Specification for Design.

Patented Sept. 20, 1921.

Application filed April 15, 1921. Serial No. 461,694. Term of patent 14 years.

To all whom it may concern:

Be it known that I, CLARENCE L. GRAVES, a citizen of the United States, residing at Eland, in the county of Shawano and State of Wisconsin, have invented a new, original, and ornamental Design for a Kitchen-Tool, of which the following is a specification, reference being had to the accompanying drawing, forming part thereof.

Figure 1 represents an inverted perspective view of a tool embodying the features of my invention, the view illustrating a semi-circular rolling-pin cleaner, scaler,

scraper, and an oval end potato dicer, grater, potato peeler slot, and Saratoga chipper slot, and

Fig. 2 another perspective view of the tool looking from the top thereof.

I claim:—

The ornamental design for a kitchen tool as shown and described.

In testimony that I claim the foregoing I have hereunto set my hand at Eland, in the county of Shawano and State of Wisconsin.

CLARENCE L. GRAVES.
